CLAIM

The ornamental design for a toy for a pet, as shown and described.

DESCRIPTION

FIG. 1 is a front perspective view of a toy for a pet, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partial enlargement of FIG. 1; and,

FIG. 9 is a partial enlargement of FIG. 1.

The dash-dash broken lines illustrate portions of the article. The dot-dash broken lines illustrate the location and bounds of the enlarged partial views shown. None of the broken lines form part of the claimed design.
